COMBINED OSCILLATOR-DETECTOR CIRCUITS

Charles Travis, Philadelphia, Pa., assignor to
Radio Corporation of America, a corporation
of Delaware

Original application April 27, 1933, Serial No.
668,231. Divided and this application Septem-
ber 3, 1937, Serial No. 162,274.

9 Claims. (Cl. 250—20)

An object of the present invention is to provide a circuit arrangement whereby a vacuum tube oscillator having a plurality of grids will generate oscillations of substantially constant frequency. 5 The present application is a division of my application, Serial No. 668,231, filed April 27, 1933, Patent No. 2,153,778, April 11, 1939.

A further object is to provide such a tube oscillator in which the oscillation strength or 10 voltage generated may be maintained substantially constant.

A still further object is to provide a combined oscillator detector, which may for example be the first detector of a superheterodyne receiver, in 15 which there is substantial freedom from frequency drift.

Another object of the invention is to further neutralize the capacity existing between the plate and a grid of a vacuum tube having a plurality 20 of grids, including a screen grid. Still other objects of the invention will be apparent to those skilled in the art as the description thereof proceeds.

Circuit arrangements showing embodiments of 25 the invention are illustrated in the accompanying drawings in which:

Figs. 1 and 2 show a vacuum tube having a plurality of grids arranged as a combined oscillator and detector;

30 Figs. 3 and 4 show circuits embodying my invention in connection with a combined oscillator detector having five grids; and

Fig. 5 shows a circuit similar to that of Fig. 1 with a neutralizing arrangement according to my 35 invention.

This invention relates in general to circuit arrangements useful in connection with a vacuum tube having several grids as disclosed in the application filed in the name of J. C. Smith on Jan. 31, 1933, Serial No. 654,421 and is in certain respects, an improvement on the circuit arrangements disclosed therein.

Referring to Fig. 1 a vacuum tube T is shown having a heater H which heats the electron emitting cathode C, and a plate 6. Interposed, or located, in the electron stream between the cathode and plate are a series of grids, 1, 2, 3, 4 and 5 arranged in the order shown, grid 1 being nearest the cathode and grid 5 being nearest the plate 6. A tunable input circuit, consisting of secondary 22 and variable condenser 18, is connected to the signal control grid 4, the lead 20 connected to the opposite side of coil 22 being connected to the output circuit of the second detector of the receiver as shown, for example, in

application Serial No. 642,544, filed Nov. 14, 1932, Patent No. 2,074,014, March 16, 1937, in the names of K. Chittick and W. L. Carlson. Lead 20 may be connected to any other source of automatic volume control bias, as well known in the art, to control the gain of the tube. Radio frequency energy of any desired frequency, such as 500 to 1500 kilocycles, may be applied to the input terminals 19 of primary 21. As shown, the local oscillator circuit includes coil 11 and variable 5 condenser 12 by which the oscillation frequency may be adjusted to produce any desired beat frequency. This circuit may be connected in a known manner to the oscillator control grid 4 through a condenser 10, a suitable grid leak resistor 9 being provided and connected to grid 4 and the cathode C. The normal steady bias of the grid 4 may be provided in known manner by a resistor 7 connected between cathode C and ground, resistor 7 being shunted by a condenser 8. 20

The plate 6 may be connected to a constant voltage source of about 250 volts through a parallel circuit comprising coil 16 and condenser 17, the latter of which may be adjustable to tune the plate circuit to the desired beat frequency, which may be, for example, 175 kilocycles. The oscillator anode electrode 2 is shown connected to the 250 volt source through a resistor 14, shunted by a condenser 15, and a tickler coil 13 which is 30 inductively coupled to coil 11. This coupling between coils 13 and 11 provides the necessary feedback of energy to the grid circuit 11—12, to cause the tube to generate oscillations. The screen grids 3 and 5 may be connected together conductively either within, or without, the tube, and 35 may have a steady positive voltage of 50 to 100 volts applied thereto from any desired voltage source (not shown) by a lead 23. Tube T can be of the well-known 2A7 type. 40

Now, I have found that, when the feedback circuit shown in Fig. 1 is used, as the signal control grid 4 is biased back more negatively by the AVC circuit, the local oscillation strength increases, that is, the magnitude of the locally produced oscillations increases. I also found that the oscillation frequency changes. In one instance I found that with a typical oscillator coil tuned by condenser 12 to 1,000 kilocycles, the frequency decreased 500 cycles per second when the bias on grid 4 was changed from -3 volts to cut-off (about -30 to -35 volts). 45

The circuit arrangement shown in Fig. 2 is essentially the same as that of Fig. 1, except that in this case the tickler coil 13 is also included in the circuit of plate 6 so that the plate current 50

- of the tube flows through it, in addition to the current of oscillator anode electrode 2. With this arrangement I found that the oscillation strength, or magnitude, decreases as the control grid 4 is given a more negative bias. I also found that at an initial oscillator frequency of 1,000 kilocycles, the frequency increased by 700 cycles as the bias on grid 4 was changed from -3 to about -30 volts.
- 10 In order to secure substantially constant oscillation strength and frequency as a variable bias is applied to control grid 4, I take a portion only of the plate feedback, and combine it with the feedback of the oscillator anode electrode 2. This 15 may be accomplished, as shown in Fig. 3, by tapping the feedback coil 13 at such a point that the two opposing effects above mentioned balance out. With a 2A7 type tube I found that the turns in the lower tapped portion 13" were one 20 third of the total number of turns in the entire tickler coil 13.

By using two separate tickler coils, each inductively coupled to coil 11 as shown in Fig. 4, I was able to secure a similar result. By making 25 the tickler coil 28, in the plate circuit, of one third the number of turns of tickler coil 13, it was found that the oscillation strength and frequency remained substantially constant, as the bias on signal grid 4 was changed over a substantial voltage range. In the particular tube used in these 30 tests, the oscillator control grid 1 was of the sharp cut-off type whereby less voltage was required to produce the desired oscillation strength, whereas, grid 4 was constructed to give remote 35 cut-off or produce a result similar to that of a variable mu tube.

In Figs. 3 and 4 I have shown the intermediate frequency tuned circuit 16, 17 inductively coupled to a secondary 24 tuned to the intermediate 40 frequency by a condenser 25. This circuit may be connected as the input circuit of an intermediate frequency amplifier 27, being connected to the grid 26 thereof. For broadcast reception circuits 45 16, 17 and 24, 25 are preferably tuned to 175 kilocycles, or any other desired beat frequency. To secure this frequency condenser 12 is initially adjusted so that the oscillation frequency is higher, or lower, than the incoming signal frequency by an amount equal to the desired beat frequency. 50 As applied to a superheterodyne receiver, therefore, I am enabled by this invention to prevent detuning of the receiver due to change, or drift, in the oscillator frequency caused by change in the grid bias of the signal control grid 4. Also, 55 it will be understood that it is equally useful where the bias of grid 4 is changed by a manual volume control means in lieu of the AVC means shown.

A further aspect of the invention is disclosed 60 in Fig. 5 where the circuit shown is generally similar to that of Fig. 1. A neutralizing circuit has been added, as shown, comprising C_N and a coil 29 inductively coupled to coil 22. Coil 29 may consist of a few reversed turns wound around 65 the low potential end of the radio frequency secondary coil 22. Even in the presence of the screen grids 3, 5 in a tube of the type above described, it is found that a capacity of about one quarter micro-microfarad (0.25) exists between 70 plate 6 and grid 4, and it is the purpose of the neutralizing circuit shown to neutralize this capacity. At the radio frequency signal voltage applied to grid 4, the load in the plate circuit is essentially capacitive. The effective plate circuit 75 capacity is always less than the physical capacity

17 used to tune coil 16 to the intermediate beat frequency. Calling f_1 =intermediate frequency, f_2 =the applied radio signal frequency; C =value of condenser 17 and C_p =effective capacity in the plate circuit

$$C_p = C \left[1 - \left(\frac{f_1}{f_2} \right)^2 \right]$$

For a low applied radio signal frequency of say 550 kilocycles and using a high intermediate or beat frequency of say 465 kilocycles, the value of C_p may be much smaller than C . Now it is very nearly exact to write:

$$\text{Grid conductance} = G_m \times \frac{C_{G-P}}{C_p}$$

As G_m is about 800 micromhos maximum, so that if C_p equals 50 micro-farads, the grid conductance is

$$\frac{800 \times 0.25}{50} = 4 \text{ micromhos}$$

equivalent to 250,000 ohms. The effect of this is substantially equivalent to connecting a resistor of this value across the coil 22 of the tuned signal circuit, and it may seriously affect both the gain and selectivity of the receiver; or the effective plate circuit capacity C_p may be much smaller, as would be the case if the intermediate frequency were higher than 465 kilocycles, thus approaching more nearly the lower frequency end 30 of the broadcast band, say 525 kilocycles. Further, as the capacity to be neutralized is very small, and its effect is degenerative and not regenerative, a neutralizing condenser of fixed value may be used; that is, the circuit is not one 35 requiring individual adjustment of the neutralizing condenser for each individual receiver.

While the neutralizing circuit described has been shown as applied to a circuit as shown in Fig. 1 it will be understood that the same circuit may be employed in connection with the circuits in Figs. 3 and 4, the coil 29 being inductively coupled to coil 22 and the neutralizing condenser C_N being connected to plate circuit 6 in the manner described.

In the circuits shown in Figs. 3 and 4, I found the following values to give satisfactory results when the source of voltage for plate 6 was 250 volts, voltage applied to screen grid 3, 5=50 to 75 volts, voltage applied to anode electrode 2=100 50 volts. This latter voltage may be easily secured, as shown, by using a resistor 14 having a value of approximately 20,000 ohms.

While I have indicated and described several systems for carrying my invention into effect, it 55 will be apparent to one skilled in the art that my invention is by no means limited to the particular organizations shown and described, but that many modifications may be made without departing from the scope of my invention, as set forth 60 in the appended claims.

What I claim is:

1. In combination, a combined oscillator and detector comprising a vacuum tube having an oscillator grid, anode electrode a signal control grid, a screen grid mounted on each side of said signal control grid, a cathode and a plate, a circuit tunable to the incoming signal frequency connected to said signal control grid, a tunable oscillator circuit connected between said oscillator grid and cathode, a circuit connected to said anode electrode and including a feedback connection to said oscillator circuit to cause said tube to generate oscillations of a frequency higher than the incoming signal frequency by a de- 75

sired beat frequency, means for applying a positive voltage to said screen grid, a plate circuit including a circuit tuned to said beat frequency and means to prevent reaction of said last named 5 circuit on said circuit tuned to the signal frequency due to the capacity coupling between said plate and said signal control grid.

2. The combination defined in the preceding claim 1 in which said reaction preventing means 10 comprises a condenser and coil connected in series, said coil being inductively coupled to the signal tuned circuit and a conductive connection between one side of said condenser and the plate of said tube.

15. 3. In combination, an electron discharge tube having at least a cathode and an output electrode, an oscillator grid, an oscillator anode and a signal grid being disposed in the electron stream between said cathode and output electrode, said 20 signal grid being disposed between the oscillator anode and said output electrode, a signal input circuit connected between the cathode and signal grid, a network, including a resonant circuit tuned to a predetermined local oscillator frequency, respectively coupling the oscillator anode and oscillator grid, an intermediate frequency circuit connected to said output electrode, means 25 reactively coupling the output electrode and said local oscillation frequency resonant circuit, and 30 means for establishing said signal grid at a predetermined negative direct current potential with respect to the cathode.

4. In combination, an electron discharge tube having at least a cathode and an output electrode, an oscillator grid, an oscillator anode and a signal grid being disposed in the electron stream between said cathode and output electrode, said signal grid being disposed between the oscillator anode and said output electrode, a signal input 35 circuit connected between the cathode and signal grid, a network, including a resonant circuit tuned to a predetermined local oscillator frequency, reactively coupling the oscillator anode and oscillator grid, an intermediate frequency circuit connected to said output electrode, means 40 reactively coupling the output electrode and said local oscillation frequency resonant circuit, means for establishing said signal grid at different negative direct current potentials with 45 respect to the cathode, in response to variations in received signal amplitude.

5. A converter network including a pentagrid tube provided with oscillator and mixer electrode sections, said oscillator section including a 50 grid electrode and an anode electrode and said mixer section including a signal grid and an output electrode, means for providing a radio frequency energy feedback from each of the oscil-

lator anode electrode and the mixer output electrode, to the oscillator grid electrode, an automatic gain control means for increasing the negative bias on the signal grid of the tube as the received signal amplitude increases and the 5 feedback from each of said electrodes being proportioned to maintain substantially constant oscillation amplitude as said negative bias varies.

6. A superheterodyne receiver including a combined local oscillator-first detector network employing a tube provided with oscillator and mixer sections, said oscillator section including a grid electrode and an anode electrode and said mixer section including a signal grid and an output electrode, automatic volume control means for 10 varying the bias of the signal grid, and means providing a radio frequency energy feedback from each of the oscillator anode and the mixer output electrode to the oscillator grid electrode, and said feedbacks being relatively proportioned 15 to render the oscillation strength and frequency substantially independent of the signal grid bias variation.

7. In a receiver as defined in claim 6, said mixer section signal grid being constructed to have a 25 remote cut-off characteristic, and said oscillator section grid has a sharp cut-off characteristic.

8. In an oscillator-detector circuit comprising a tube provided with oscillator section electrodes and detector section electrodes, said detector section including a signal input electrode and an output electrode, a source of signals coupled to the signal input electrode of the detector section, a local oscillation circuit coupled to the oscillator electrodes to produce oscillations of a frequency 35 differing from the signal frequency by an intermediate frequency, means providing radio frequency energy feedback between the output electrode of the detector section and the said oscillation circuit, and means for varying the direct 40 current voltage of said signal input electrode thereby to control the amplitude of the intermediate frequency energy.

9. In a detector-oscillator system using a tube provided with oscillator section electrodes and detector section electrodes, said detector section including input electrodes and an output electrode, a source of signals coupled to the input electrodes of the detector section, a local oscillation circuit coupled to the oscillator electrodes, a beat frequency output circuit coupled to the detector section output electrode, means feeding back radio frequency energy from the said output electrode to said oscillation circuit, and automatic gain control means responsive to an increase in signal amplitude for decreasing the 50 local oscillation amplitude.

CHARLES TRAVIS.
